UNITED STATES PATENT OFFICE

159,335

AUTOMOTIVE VEHICLE TOP

Clare H. Graham, Detroit, Mich., assignor to General Motors Corporation, Detroit, Mich., a corporation of Delaware

Application June 25, 1949, Serial No. 3,537

Term of patent 7 years

(Cl. D14—27)

To all whom it may concern:

Be it known that I, Clare H. Graham, a citizen of the United States, being a resident of Detroit, county of Wayne, State of Michigan, have invented a new, original, and ornamental Design for an Automotive Vehicle Top, of which the following is a specification, reference being made to the accompanying drawing, forming a part thereof.

In the drawing:

The dotted lines shown in the figures of the drawing are for illustrative purposes only.

I claim:

The ornamental design for an automotive vehicle top, substantially as shown and described.

CLARE H. GRAHAM.
